ATTORNEYS.

UNITED STATES PATENT OFFICE.

WILLIAM HENRY SHEPHERD, OF PITTSSTON, PENNSYLVANIA.

COAL-CLEANER.

SPECIFICATION forming part of Letters Patent No. 291,788, dated January 8, 1884.

Application filed October 18, 1883. (No model.)

To all whom it may concern:

Be it known that I, WILLIAM HENRY SHEPHERD, of Pittston, in the county of Luzerne and State of Pennsylvania, have invented a new and useful Improvement in Coal-Cleaners, of which the following is a full, clear, and exact description.

Reference is to be had to the accompanying drawings, forming part of this specification, in which similar letters of reference indicate corresponding parts in both the figures.

Figure 1 is a sectional side elevation of my improvement. Fig. 2 is a sectional end elevation of the same, taken through the line *x x*, Fig. 1.

The object of this invention is to provide a mechanism for separating slate from coal as the said coal passes down the chutes from the grading-screens.

The invention consists in a coal-cleaner constructed with stationary grate-bars placed in an opening in the chute-bottom, and alternating with movable grate-bars connected by cross-bars with sliding rods connected by bars with a rock-shaft connected with and driven from a rotary crank-shaft, as will be hereinafter fully described and claimed.

A represents a coal-chute. B is a shaft which revolves in bearings in standards C, attached to the chute A.

To one end of the shaft B are attached a fast pulley, D, and a loose pulley, E, to receive a driving-belt from a steam-engine or any other convenient power. To the other end of the shaft B is attached a crank-wheel, F, to which is pivoted the end of a connecting-bar, G. The other end of the bar G is pivoted to a crank-arm, H, attached to a rock-shaft, I, journaled in bearings in standards J, attached to the chute A.

To the shaft I are attached two crank-arms, K, to which are pivoted short connecting-bars L. The other ends of the bars L are pivoted to the middle part of the bars M, to the ends

of which are rigidly attached the upper ends 45 of the rods N. The rods N pass down through guide-holes in the sides of the chute A, and to their lower ends are attached cross-bars O, to which are attached grate-bars P. The grate-bars P, as the crank-shaft I is rocked by the 50 revolution of the crank-shaft B, are raised and lowered through an opening, Q, in the bottom of the chute A. The grate-bars P alternate with stationary grate-bars R, placed in the opening Q and secured to the chute A. 55 With this construction, as the coal in passing down the chute A passes over the grate-bars P R, the successive rising of the grate-bars P above and descending below the level of the grate-bars R turns the pieces of slate that 60 may be with the coal edgewise, and causes them to pass through the spaces between the said grate-bars and drop to the ground, while the irregular form of the pieces of coal prevents the said coal from passing through the 65 said spaces and causes it to pass on down the chute.

The grate-bars P R may be flat or round; but I prefer to make them flat, as operating more effectively in turning the pieces of slate 70 edgewise.

Having thus described my invention, what I claim as new, and desire to secure by Letters Patent, is—

The combination, with the chute A, having 75 opening Q, of the stationary grate-bars R, the movable grate-bars P, the connecting-bars O, the sliding rods N, the connecting-bars M L G, the rock-shaft I, provided with crank-arms K H, and the revolving crank-shaft B, substantially as herein shown and described, whereby the pieces of slate will be made to pass out between the grate-bars, as set forth.

WILLIAM HENRY SHEPHERD.
